UNITED STATES PATENT OFFICE.

CURTIS WALTER LESLIE, OF PITTSBURG, PENNSYLVANIA; THERESA A. LESLIE ADMINISTRATRIX OF SAID CURTIS WALTER LESLIE, DECEASED.

MAGAZINE TORPEDO-CANE.

SPECIFICATION forming part of Letters Patent No. 761,309, dated May 31, 1904.

Application filed November 18, 1903. Serial No. 181,630. (No model.)

To all whom it may concern:

Be it known that I, CURTIS WALTER LESLIE, a citizen of the United States, residing at Pittsburg, county of Allegheny, and State of Pennsylvania, have invented certain new and useful Improvements in Magazine Torpedo-Canes, of which the following is a specification.

This invention relates to magazine torpedo-canes.

10 My invention relates to that class of canes adapted to contain a quantity of explosive caps and to automatically feed them in succession to an exploding-mortar on the lower end of the cane, so that when the cane is struck or tapped on the ground or other object the mortar will explode the cap. Canes of this character are useful as toys for children or public demonstrations in parades, Fourth-of-July celebrations, and at other times where

15 it is desired to employ a safe, attractive, and convenient detonating device.

The object of my invention is to provide a detonating-cane of improved and novel construction which can be produced at comparatively small expense, will be reliable in operation, and neat in appearance.

20 Other objects are to simplify the construction and provide an improved feed device and a novel form of mortar whereby a large number of caps can be fed from a magazine in the cane one at a time in an automatic manner on successive operations of the cane and exploded by the mortar at will without danger of exploding any of the caps in the magazine.

25 Other objects of the invention and the details of construction are clearly disclosed in the following description, while the novel features are set forth in the appended claims.

30 In the accompanying drawings, Figure 1 is an exterior view; Fig. 2, a view with one-half of the cane removed to disclose the interior construction, the mortar and cut-off being shown in section and a cap in the mortar ready for explosion; Fig. 3, a like view, but showing the position of the parts after the cap has been exploded and another cap let through the cut-off in position to be fed afterward to the mortar; Fig. 4, a perspective detail of the cut-off; Fig. 5, a perspective detail of the ferrule.

The cane is made in two parts 1 and 2, glued or otherwise secured together along the line 3, and is provided with a bore 4. On the lower end of the cane is a ferrule 5, having a solid head at its lower end, which bears against the end of the cane and is provided with the aperture 6. The ferrule has slots 7 and 8 on opposite sides and another slot, 9. The mortar 10 is preferably of metal and cup-shaped and provided with pins 11 and 12, which slide in the slots 7 and 8. Projecting centrally of the mortar, from the base into the interior thereof, is a pin 13, which is adapted to fit the opening 6. The mortar is provided with an aperture 14 for the discharge of the smoke and to vent the force of the explosion. The mortar is of an internal diameter such that it is adapted to snugly yet easily slide on the ferrule 5.

Slidable transversely through the cane in suitable parallel slots is a cut-off 15, made of a single piece of metal having a stop 16 and parallel shelves 17 and 18, the stop 16 being on the end of the shelf 18 to limit the play of the cut-off in one direction and the connecting portion 19 limiting the play of the cut-off in the other direction. The shelf 18 has an opening 20 of a proper size to permit passage of the caps 21 therethrough when said opening is in alignment with the bore of the cane, which will occur when the cut-off is moved inwardly, as shown in Fig. 3. The shelf 17 is imperforate and adapted to hold a cap after it has passed through the opening 20, as shown in Fig. 3. To automatically retract the cut-off, I provide a leaf-spring 22, having a hooked end 23 removably engaged in an opening 24 in the cut-off. The other end of the spring is secured to the ferrule at 25, and the slot 9 is adapted to receive the spring when the spring is pressed toward the cane, as shown in Fig. 3.

A suitable number of the caps are interposed in the cane through the movable top or head 26 thereof and rest one upon the other, as shown in Figs. 2 and 3, being supported by the blank portion of the shelf 18 of the cut-off, the parts being in the position shown in Fig. 2. On pressing the mortar against

- any object it slides on the cane and the pin 13 enters the bore 4, while the mortar presses the spring 22 toward the cane, thereby moving the cut-off to the position shown in Fig. 5 3, and the lowest cap then drops through the opening 20 and rests on the shelf 17. Immediately the cane is raised the weight of the mortar, supplemented by the action of the spring 22, causes the mortar to move to the 10 position shown in Fig. 2, and the shelf 17 being removed from under the cap, which is dropped through the opening 20, said cap drops into the mortar, as shown, and the remaining caps in the magazine are supported 15 by the blank portion of the shelf 18. Upon sharply striking the mortar against any object the cap within the mortar will be exploded, but not until the pin 13 enters the bore 4, so that accidental explosion of the 20 remaining caps is rendered impossible. The smoke and fire pass out through the vent 14. As the mortar 10 moves onto the cane during this operation the spring 22 is made to slide the cut-off inwardly to let another cap through 25 the opening shelf 20 onto the shelf 17, the parts being then in the position shown in Fig. 3. Immediately the cane is raised the cap drops down into the mortar and the cane is then ready for another explosion.
- 30 Having thus described my invention, what I claim as new, and desire to secure by Letters Patent, is—
1. In an explosive or detonating cane, the combination with a cane having a bore to receive the caps, of a mortar slidably relatively to the cane and provided with a pin adapted to enter the bore when the cap in the mortar is being exploded.
  2. In an explosive or detonating cane, the 40 combination with a magazine, of a cut-off to regulate the feed of the caps, a mortar slidably relatively to the cane and coacting with the cut-off and a pin adapted to enter the part of the magazine which discharges into the mortar, prior to the explosion.
  3. In an explosive or detonating cane, the 45 combination with a magazine, of a cut-off controlling the feed of the caps from the magazine, a spring acting directly on the cut-off
- and a mortar for exploding the caps, said mortar operating the cut-off. 50
4. In an explosive or detonating cane, the combination with a magazine for the caps, of a cut-off controlling the feed of the caps from the magazine, a leaf-spring coacting with the cut-off 55 to actuate it and a mortar for exploding the caps, said mortar operating the cut-off.
5. In an explosive or detonating cane, the combination with a magazine, of a cut-off controlling the feed of the caps from the magazine, a leaf-spring coacting with the cut-off 60 to actuate it, and a mortar for exploding the caps fed from the cut-off, said mortar being adapted to engage with the leaf-spring when said mortar is in operation and thereby operating the cut-off. 65
6. In an explosive or detonating cane, the combination with a magazine for holding the caps, of a cut-off having two shelves one of which has an opening to let the caps through 70 onto the other shelf when in one position and to sustain the caps when the cut-off is in another position, and the other shelf being adapted to hold a cap after it is fed through the opening aforesaid and to release the cap 75 when the cut-off is thereafter actuated, and a mortar for exploding the caps fed from the cut-off.
7. In an explosive or detonating cane, the combination with a magazine for holding the 80 caps, of a cut-off having two shelves one of which has an opening to let the caps through onto the other shelf when in one position and to sustain the caps when the cut-off is in another position, and the other shelf being 85 adapted to hold a cap after it is fed through the opening aforesaid and to release the cap when the cut-off is thereafter actuated, a leaf-spring for actuating the cut-off, and a mortar for exploding the caps fed from the cut-off and 90 coacting with the leaf-spring to operate the cut-off.
- In testimony whereof I hereunto affix my signature in presence of two witnesses.
- CURTIS WALTER LESLIE.
